UNITED STATES PATENT OFFICE.

JOSIAH S. BRIDGES, OF CHICAGO, ILLINOIS, ASSIGNOR TO KOOLBITE TOY COMPANY, OF CHICAGO, ILLINOIS, A CORPORATION OF ILLINOIS.

DESIGN FOR A TEETHING TOY.

43,919.

Specification for Design.

Patented Apr. 29, 1913.

Application filed October 21, 1912. Serial No. 727,087. Term of patent 14 years.

To all whom it may concern:

Be it known that I, JOSIAH S. BRIDGES, a citizen of the United States, residing at the city of Chicago, county of Cook, and State of Illinois, have invented a new, original, and ornamental Design for a Teething Toy, of which the following is a specification, reference being had to the accompanying drawing, forming part thereof, in which—

I claim—

The ornamental design for a teething toy, as shown.

JOSIAH S. BRIDGES.
